EXPOSING APPARATUS FOR PHOTOGRAPHIC CONTACT PRINTING

Lodewijk Pieter Frans van der Grinten, Venlo, Netherlands, assignor to Chemische Fabriek L. van der Grinten, Venlo, Netherlands, a company of the Netherlands

Application July 16, 1947, Serial No. 761,314
In the Netherlands July 17, 1946

2 Claims. (Cl. 95—77.5)

1

This invention relates to an exposing apparatus for photographic contact printing wherein flexible sheet materials such as an original and a light-sensitive film or paper are exposed to light in close contact with each other. The apparatus involved is of the type equipped with a hollow cylinder of light-pervious material which surrounds a light source, and with a flexible applying sheet for applying and holding the sheet materials to be exposed against the surface of the cylinder.

In exposing apparatus of this type the cylinder generally consists of glass and the applying sheet is made of cloth or the like. The material to be exposed is usually rotated with the cylinder or pushed over its surface in the course of exposure, so that exposure takes place while the material is moving. In some cases it is desirable to expose the material while it is stationary; for example, when the originals to be copied vary in transparency or translucency and require different periods of exposure for proper treatment. In such cases an apparatus adapted for stationary exposure is the simplest to use. In apparatus of that type the size of the material that can be exposed is limited according to the diameter of the cylinder, and this is important because the diameter of the cylinder is subject to practical limitations. It is easier to obtain a flawless glass cylinder with a small diameter, and the cylinder must be flawless in the case of stationary exposure. Secondly, a cylinder of small diameter makes it possible to use a lamp of lower power, also one of smaller length in the case of tubular lamps, and this presents advantages with respect both to the cost of electric current and to the cooling of the lamp.

In order to have the size of the sheet material that can be exposed as large as feasible it must be possible to use the largest feasible part of the circumference of the cylinder for exposure. This becomes possible if the flexible applying sheet is made movable onto and from the cylinder as the cylinder is rotated back and forth for the introduction and the removal, respectively, of the material to be exposed. To accomplish this, however, the applying sheet normally must be fastened to the cylinder along a generating line of its surface, and that involves other difficulties. In such event a relative adjustment of the applying sheet and the cylinder, e. g., in order to remove glass flaws from the field of exposure or to correct any slanting tendency of the applying sheet, is not possible. Also, the replacement of a glass cylinder broken or cracked during operation is a complicated matter.

2

According to the present invention, these difficulties may be overcome by providing the applying sheet with a lengthening extension in the form of two drawing members located on either side of the sheet beyond its breadth, such as spaced parallel cords, wires, tapes, belts, ribbons, ropes, etc., and passing the interconnected applying sheet and extension about the cylinder in the form of a loop so that portions of the same cross each other and extend away from the cylinder in opposite directions with the applying sheet passing between the two drawing members where they cross.

This and other features of the present invention will be apparent from the following detailed description of an illustrative embodiment thereof and from the accompanying illustrative drawing which forms a part hereof, and in which:

Fig. 1 is a vertical cross section of an exposing apparatus embodying the invention;

Fig. 2 is a diagrammatic representation of the manner of arranging the applying sheet and its drawing members about the cylinder; and

Fig. 3 is a fragmentary plan view showing details of one manner of connecting the applying sheet with the drawing members.

As seen in Figs. 1 and 2, a glass cylinder 1 that is to be used for exposure is arranged horizontally so as to be rotatable about its axis. The cylinder is made rotatable by having its surface rest on upper portions of horizontally spaced series of rotary discs 3 and 4 and which are carried on spaced horizontal shafts or rods 3a and 4a, respectively. These shafts or rods are mounted in the frame 20. Located inside and on the axis of cylinder 1 is a tubular lamp 2, which is slightly longer than the cylinder. A flexible applying cloth is designated 5 and possesses a length at least sufficient to encircle the cylinder 1. The ends of this cloth are provided with transverse rods 6 and 7 (Fig. 1), which extend through terminal hemis 5a and 5b, respectively, of the cloth so that the ends of the rods project beyond the breadth of the cloth on either side thereof as seen, for example, at 6a and 6b in Fig. 3.

The projecting ends of the rods 6 and 7 are interconnected by spaced, parallel flexible drawing members 8 and 9, which may be ribbons, cords, or the like as mentioned above. Thus the applying sheet 5 and the drawing members 8 and 9 together form an endless belt member. As may be seen particularly from Fig. 2, this endless belt member is passed or wrapped about the glass cylinder in the form of a loop thereon, and where the belt portions extending from the loop across each other to leave the cylinder, i. e., where

the sheet 5 itself moves to and from the surface of the cylinder, the body of the sheet 5 lies and may pass freely in the space between the two drawing members 8 and 9. Thus the applying sheet 5 is rendered capable of being passed or wound onto the cylinder 1 so far that it will cover the full 360° of the surface of the cylinder; which is to say that the glass cylinder can now perform one complete revolution and can accommodate sheet material to be exposed, between itself and the sheet 5, over the full sweep of its circumference. A complete utilization of the surface of the glass cylinder is therefore made possible.

As shown in Fig. 1, the portions of the applying sheet 5 and the drawing members 8 and 9 that extend oppositely away from the cylinder 1 lead from it over spaced horizontal pulleys or rollers 10 and 11 below the cylinder, and thence together again beneath these rollers in endless belt arrangement. One of the rollers, as at 10, is held in the frame 20 below and toward the back of cylinder 1, while the other roller 11 which receives the sheet 5 is held between forward extensions 20a of the frame at the front of the apparatus. The length of the endless belt member and the forward spacing of the front roller 11 are such that the portion of sheet 5 extending between cylinder 1 and roller 11 constitutes a table surface at 12 ahead of the cylinder. A fixed guiding plate 13 presents a flat surface just below the applying sheet at 12, to support the applying sheet there so that an original and a light-sensitive sheet to be exposed may be easily placed on it for movement by it into contact with the exposing cylinder.

In order to keep the requisite tension in the endless belt member, the drawing members 8 and 9 may each be made with an elastic portion such as a tension spring 14. The frame 20 is provided with a covering hood 21 for complete enclosure of the exposing cylinder. Hood 21 is hinged to the frame at 22 and has a handle 23 to facilitate opening the hood.

When a photo copy is to be made, the original to be copied is placed on the surface of the applying sheet 5 at 12, together with the light-sensitive sheet material to be exposed. Then the applying sheet is pushed into the apparatus in the direction of arrow 15, the glass cylinder 1 thus being rotated until the materials have been moved or wound completely thereupon in contact with its surface. These materials may possess any width accommodated by the axial length of the cylinder and any length up to a maximum equalling the outside circumference of the cylinder. The materials thus applied to the surface of the cylinder are held there by the applying sheet and exposed to the light transmitted through the glass cylinder from the tubular lamp. After due exposure the applying sheet 5 is moved back in the direction of arrow 16, the glass cylinder thus also being turned back so that the sheet materials arrive again at the table location 12 where they may be removed for replacement by another set of materials to be exposed.

A stripper 17 has an edge held next to the surface of the cylinder 1 above plate 13, in position to strip off any material that may tend to stick to the cylinder as it is turned back for the removal of materials after an exposure. The

stripper 17 is made impervious to the light from lamp 2, and it is so disposed between the lamp and the table surface at 12 that it acts not only as a stripper but also as a light screen to keep the effective light from falling on sensitive material at 12.

I claim:

1. An apparatus for exposing flexible sheet materials in photographic contact printing, comprising a hollow rotatable cylinder of light-pervious material, a light source within the cylinder and a flexible sheet for applying said sheet materials to the surface of the cylinder for exposure, said flexible applying sheet being of a length sufficient to substantially encircle the cylinder and having connected with at least one of its ends a lengthening extension in the form of spaced flexible drawing members located on either side of the body of the sheet, the interconnected sheet and extension passing about the cylinder as a loop thereon from which portions of said sheet and extension, respectively, extend in opposite directions so that they cross each other adjacent the cylinder with the sheet passing between the spaced drawing member, said drawing members being connected with both ends of said sheet so that the sheet and the drawing members together constitute an endless belt.
2. An apparatus for exposing flexible sheet materials in photographic contact printing, comprising a light-pervious cylinder rotatable about a horizontal axis, a light source within the cylinder on its axis, spaced horizontal rollers below and parallel to the axis of the cylinder, one roller back of the cylinder and another spaced in front thereof, a flexible applying sheet of a length sufficient to substantially encircle the cylinder and having a lengthening extension connected with the ends of the sheet to form therewith an endless belt member, said extension comprising spaced flexible drawing members located on either side of the body of the sheet, said belt member passing about the cylinder as a loop thereon from which portions of the sheet and the drawing members, respectively, extended in opposite directions in crossed relationship at the lower side of the cylinder with the sheet passing forward through space between the drawing members, the extending portions of said sheet and said drawing members leading to and over said front and said back rollers, respectively, and then together beneath said rollers, the sheet portion extending between the cylinder and said front roller constituting a table surface for receiving sheet materials to be applied to and exposed on the cylinder, said drawing members comprising elastic portions holding the belt member on the cylinder and the rollers under tension.
